UNITED STATES PATENT OFFICE.

FREDERICK MERTSHEIMER, OF DENVER, COLORADO.

PRESSURE-RETAINING DEVICE FOR FLUID-PRESSURE BRAKES.

SPECIFICATION forming part of Letters Patent No. 766,642, dated August 2, 1904.

Application filed January 2, 1904. Serial No. 187,517. (No model.)

To all whom it may concern:

Be it known that I, FREDERICK MERTSHEIMER, of Denver, county of Denver, and State of Colorado, have invented a new and useful

5 Improvement in Pressure-Retaining Devices for Fluid-Pressure Brakes, of which the following is a specification.

This invention has reference to the system of fluid-pressure-operated brakes in which the 10 brakes are actuated by brake-cylinders in controllable communication with auxiliary reservoirs charged through a train-pipe from a main source of fluid under pressure; and the invention has reference more particularly to the 15 mechanism now commonly used in connection with systems of this type for retaining a working pressure in the brake-cylinder after it has been operated to apply brakes, to the end that the brake-cylinder will continue to be operative during the recharging of the auxiliary 20 reservoirs. In the operation of this system of brakes a definite pressure from the main source of supply is maintained throughout the train-pipe and auxiliary reservoirs, which 25 pressure when the brakes are to be applied is relieved, and this action, through the medium of a triple valve situated in the communication between the auxiliary reservoirs and the brake-cylinder, will admit pressure to the 30 brake-cylinder from the auxiliary reservoir, and this pressure acting on the brake-piston will apply the brakes. When the brakes are to be released, the previous pressure in the 35 train-pipe is reestablished, which action will by means of the triple valve open communication of the brake-cylinder with the atmosphere and simultaneously recharge the auxiliary reservoir.

The mechanism for retaining a working 40 pressure in the brake-cylinder while the auxiliary reservoir is being recharged is usually in the form of a valve applied in such manner as to control the exhaust of pressure from the brake-cylinder, which valve is of such 45 form and construction that it will permit the escape of the fluid from the brake-cylinder only when at a certain predetermined pressure, usually fifteen pounds, the result being that the valve will retain this pressure in the 50 brake-cylinder under all conditions, so that

while the auxiliary reservoir is being recharged this retained pressure is available for actuating the brakes for retarding the acceleration of the train.

It has been found in practice that under 55 certain conditions—for instance, light unloaded cars on a uniform moderate downgrade—a retaining-valve formed to retain a pressure of fifteen pounds is sufficient; but there are conditions encountered which demand a much 60 higher retained pressure—such, for instance, as heavily-loaded cars on mountain grades. It is not feasible to employ a single retaining-valve to meet both conditions, for the pressure retained would be such that under the 65 conditions first named the friction of the brakes on the wheels would be too great and such as to cause sliding or skidding. It is necessary, therefore, that there be available two different retained pressures; and my invention consists, therefore, in combining with a mechanism for retaining a predetermined pressure in the brake-cylinder a device for retaining a greater pressure and suitable connections whereby one or the other of said devices may be brought into action at will. 70

In the accompanying drawings, Figure 1 is a bottom plan view of a car equipped with an air-brake system and showing how my invention is applied thereto. Fig. 2 is an end elevation of the same as viewed in the direction of the arrow in Fig. 1, showing my improved pressure-retaining device and its connection with the system. Fig. 3 is a vertical longitudinal sectional view, on an enlarged scale, of 85 the pressure-retaining device shown in Fig. 2.

Referring to the drawings, and particularly to Fig. 1, 1 represents a train-pipe extending throughout the length of the train. 2 represents an auxiliary reservoir, 3 a brake-cylinder, and 4 a triple valve, which latter controls communication between the train-pipe and auxiliary reservoir, between the auxiliary reservoir and brake-cylinder, and between the brake-cylinder and external atmosphere, as 90 through port 5. As is well understood by those skilled in the art, a definite pressure is maintained in the train-pipe and auxiliary reservoirs, which pressure on being reduced 95 by the engineer by mechanism under his con- 100

trol acts, through the triple valve, to connect the auxiliary reservoir with the brake-cylinder and applies the brakes, which latter are released by the reestablishment of the previous pressure in the train-pipe, which action opens the brake-cylinder to the external atmosphere and recharges the reservoir. In order to retain a working pressure in the brake-cylinder, it is usual to connect with the exhaust-port on the triple valve, through the medium of a connecting-pipe 6, extended upward at the end of the car, a pressure-retaining valve 7, such as indicated in Fig. 3, the purpose being to retain a predetermined working pressure in the brake-cylinder, so that while the reservoirs are being recharged the brakes may still act to retard the acceleration of the train. As shown in Fig. 3, this pressure-retaining valve comprises a casing 8, open to the atmosphere through port 9 in the bottom of the casing, and having mounted therein a vertically-movable weighted valve 10, which controls a port 11 in the casing communicating with the exhaust of the triple valve through the pipe 6. This valve being weighted so as to retain a pressure, say, of fifteen pounds is only lifted to open communication with the atmosphere by a higher pressure from the brake-cylinder, so that when the pressure is reduced to this amount the weighted valve seats itself, closes communication with the outside, and retains the pressure in the brake-cylinder. When it is not desired to retain a pressure in the brake-cylinder, the valve is cut off from communication with the pipe 6 by a cock 12, applied in the pipe 6 and of such form that it may be turned to close communication between the pipe and valve and open the pipe to the atmosphere through port 13. The foregoing parts may be of the usual and ordinary construction, and except in so far as hereinafter indicated and as combined with my improved device they form no part of the present invention.

In carrying out my invention I provide a high-pressure device 14 of a form and construction which will retain in the brake-cylinder a greater pressure than that retained by the valve 7, and I so apply this device that one or the other may be used, as desired. This high-pressure device comprises a valve-casing 15, within which is a chamber 16, open to the atmosphere, as at 17, and connected by port 18 through the bottom of the casing with a branch pipe 19, connected in turn with the pipe 6. Port 18 is formed at its upper end with a valve-seat 20, against which is adapted to close a valve 21 on the bottom of a vertically-movable weight 22, mounted in chamber 16, the construction being such that fluid under pressure in pipe 19 will lift the weight and open the valve, and thus establish communication with the atmosphere only when said pressure exceeds that exerted by the weight. The re-

lation of the weight 22 to that of the weighted valve 10 is such that the former will act to retain a higher pressure in the brake-cylinder, so that for conditions where the low-pressure retaining-valve is not suitable the high-pressure valve may be employed. These relations of the valves may of course be varied to meet the conditions encountered.

In order that the high-pressure device may act to perform its functions without interference from the low-pressure valve, I provide in the pipe 6 at a point between the connection therewith of the branch pipe 19 and the low-pressure valve a cut-off 23, preferably in the form of a plug-valve formed so that it may be turned to cut off communication of the pipe 6 with the low-pressure valve, under which conditions the exhaust from the brake-cylinder will pass through the branch pipe 19 and acting on the high-pressure valve will find its escape only when it is great enough to open the high-pressure valve.

In the operation of the system equipped with my improved device when the conditions are such as to demand the retention only of a light working pressure in the brake-cylinder plug-valve 23 is opened, so as to allow the exhaust to pass to the low-pressure-retaining valve, which will act to retain a light working pressure in the brake-cylinder. The fact that the high-pressure valve is also and at all times in communication with the exhaust of the brake-cylinder will not affect the operation of the low-pressure valve, for the reason that it operates only at a high pressure. When, on the other hand, the conditions are such as to demand the retention of the higher working pressure in the brake-cylinder, valve 23 is closed, so as to cut out the low-pressure valve, under which conditions the exhaust can only find its escape through the high-pressure valve when its pressure is such as to operate said valve, and consequently a higher pressure will be retained in the brake-cylinder.

When it is not desired to employ either of said pressure-retaining devices, cut-off cock 12 is turned to close communication between the pipe 6 and the low-pressure valve and open said pipe to the atmosphere through port 13. In this position of the parts the exhaust will pass to the atmosphere and will not be obstructed by either of the retaining-valves.

Having thus described my invention, what I claim is—

1. In a device of the class described the combination with a brake-cylinder of means for supplying fluid under pressure thereto, a pair of pressure-valves in normal communication with the cylinder and operable independently by different pressures in the latter and means for closing communication between the low-pressure valve and cylinder at will.

2. In a device of the class described the combination with a brake-cylinder, of means for

supplying fluid under pressure thereto, a pair of pressure-valves in normal communication with the cylinder and operable independently by different pressures in the latter and a 5 cut-off valve for closing communication between the low-pressure valve and cylinder at will.

3. In a device of the class described the combination with a brake-cylinder, of an exhaust-10 duct leading therefrom, a low-pressure valve connected with said duct, a branch duct leading from the exhaust-duct, a high-pressure valve connected with the branch duct, both of

said valves being in normal communication with and independently operable by different 15 pressures in the cylinder, and a cut-off valve in the exhaust-duct at a point beyond the branch duct for closing communication between the low-pressure valve and cylinder at will.

In testimony whereof I hereunto set my 20 hand, this 10th day of December, 1903, in the presence of two attesting witnesses.

FREDERICK MERTSHEIMER.
